UNITED STATES PATENT OFFICE.

EDWARD F. KUNATH, OF JERSEY CITY, NEW JERSEY, ASSIGNOR TO UNDERWOOD TYPEWRITER COMPANY, OF NEW YORK, N. Y., A CORPORATION OF NEW JERSEY.

TYPE-WRITING MACHINE.

No. 857,288.

Specification of Letters Patent.

Patented June 18, 1907.

Application filed July 8, 1905. Serial No. 268,854.

To all whom it may concern:

Be it known that I, EDWARD F. KUNATH, a citizen of the United States, residing in Jersey City, in the county of Hudson and State of New Jersey, have invented certain new and useful Improvements in Type-Writing Machines, of which the following is a specification.

This invention relates to the ribbon mechanism of typewriting machines and particularly to means for bringing into use different colors of ribbon at will.

I provide two or more separate ribbons of different colors and movable independently of one another to cover the printing point. In the preferred form of the invention, the ribbons are superposed or placed one in front of another in front of the platen, and means are provided for causing either ribbon to cover and uncover the printing point during the type strokes while the other ribbon remains idle.

I illustrate my invention as applied to the well known "Underwood" front strike writing machine, in which spools carrying the usual ribbon are mounted upon vertical axes one at each side of the printing point in front of the platen. Behind said ribbon, I stretch a short ribbon of red or other special color, which is wound by means of spools placed at the extreme sides of the machine. The short special ribbon may in some cases be endless; and in such a case two other spools are placed at the front of the machine so that the endless ribbon winds around four spools and incloses the usual ribbon and its spools. Winding means are provided for the endless ribbon; and I also provide an individual carrier or vibrator for each ribbon, one carrier in front of the other. Said carriers are shown movable up and down by means of levers. The latter may be substantially like those commonly used in the "Underwood" machine, and may be mounted side by side, either lever being called into operation at the type strokes. The lever-operating mechanism includes the usual universal bar frame, which reciprocates at each type stroke. Upon said reciprocating member I mount actuators, one for each of said ribbon-vibrating levers; said actuators being shiftable to engage either one or the other lever. Means are provided for detaining the actuators in either shift position. Means are

also provided whereby the actuators may be held in such a position that neither lever will be operated, so that neither ribbon is caused to cover the printing point at the type strokes, this being a convenience when making stencils. Other objects and advantages will hereinafter appear.

In the accompanying drawings, Figure 1 is a perspective view illustrating my invention applied to an "Underwood" front strike writing machine. Fig. 2 is a perspective view of the duplex ribbon actuator. Fig. 3 is a sectional elevation of the machine taken from front to rear.

Upon the front side of a revoluble platen 1 strike types 2 mounted upon type bars 3, the latter being operated by upright levers 4 connected to key levers 5. In front of the platen is the usual ribbon 6, winding back and forth upon spools 7, 8, the latter mounted on vertical shafts 9, 10, provided with pinions 11 meshing with pinions 12, the latter rigidly connected to ratchet wheels 13 operated by pawls 14, the latter pivoted upon rock-arms 15 fixed upon a rock shaft 16 having an arm 17; and engaging with the latter is a rock arm 18 extending forwardly from an upright rocking-frame 19 to which is pivoted at 20 ears formed upon the rear end of a horizontal table or reciprocating frame 21, the latter having fixed upon its front portion a segmental universal bar 22 operating upon the type bars. As so far described the parts are in common use upon said "Underwood" machine. Said ribbon 6 is threaded through an upstanding carrier 23 loosely connected at 24 to the front end of a lever 25, which is pivoted upon a shoulder screw 26, the latter threaded into a bracket 27 fixed upon the rear side of a horizontal shift rail 28. Said lever 25 has an arm 29 extending up from said pivot 26 and provided with a laterally projecting pin 30, whereby the lever is operated during the backward and forward movement of said universal bar frame or table 21, in a manner presently to be explained.

In rear of the main ribbon 6, I stretch a supplemental ribbon 31 of red or other special color, which extends between spools 32, 33, pivoted at the extreme sides of the machine, so that the spools, 7, 8, lie between said spools 32, 33. The latter, it will be understood, may be of any usual or ordinary type, and may be provided with any suitable

or ordinary mechanism for winding the ribbon back and forth between them independently of the spools 7, 8. Since, however, the special ribbon is infrequently used, it is not always necessary to provide a long ribbon, and for convenience I illustrate in this instance a short ribbon, which I make endless. Spools 34, 35 are mounted in front of the spools 7, 8, and the endless ribbon 31 is carried therearound, as seen at Fig. 1, so that said ribbon 31 completely incloses or surrounds the spools 7, 8 with their attached ribbon 6. The ribbon 31 will be kept taut by means of a spring 35, which is connected at one end to a fixture and at the other end to a lever 36, upon which the spool 34 is pivoted, so that the latter is forced out or in a direction to tighten the ribbon 31.

The special ribbon may be caused to feed back and forth by means of a bevel pinion 37 on the spool shaft 9, meshing with a bevel gear 38 upon a horizontal shaft 39, which is connected by bevel pinions 39^a and 32^a with the spool 32. During the winding of the spool 7 the spool 32 is caused to rotate in one direction, while during the unwinding of the spool 32 is turned in the opposite direction. It will be understood that spool 32 will be connected to spool shaft 10, in case it is desired not to use an endless ribbon but to coil the ribbon back and forth upon the spools 32 and 33.

The ribbon 31 is threaded through a ribbon carrier 40 mounted directly behind the carrier 23, and having ears 41 to embrace a fixed vertical guide 42, which in said machine is the type-guiding post. Said ears 41 it will be understood also confine the carrier 23 against lateral displacement. The ribbon carriers are guided between said type post 42 and a fixed abutment 43; a spring 44 being provided upon the carrier 40 for pressing both carriers lightly forward against said post 42. The carrier 40 is pivoted at its lower end to a lever 45, similar to the lever 25 and alongside thereof, and pivoted upon the shoulder 26 and having an upwardly extended arm 46 provided with a projecting pin 47 whereby it is operated.

It will be seen that the ribbon-guiding pins 40^a of the carrier 40 are set in line with the forked main portion of said carrier, to correspond with the direction taken by the ribbon 31, which extends substantially straight across the machine, while the pins 23^a of the front carrier 23 are set forward of the fork of said carrier, to correspond with the forward and outward direction taken by the ribbon of the spools 7, 8. The pins 40^a are thus well separated from the pins 23^a, and the carriers move freely up and down independently of one another.

Upon an upstanding bracket 48 secured upon the table 21 by means of screws 49, I mount a pair of similar actuators 50, 51 hav-

ing deep vertical slots, 52, 53 to engage respectively the projecting lever pins 47, 30. Said actuators are preferably integral, being formed upon the ends of a vertical plate 54 shiftable along the bracket 48 and being held upon said plate by shoulder screws 55, which are inserted with a horizontal slot 56 in said vertical plate 54; said slot enabling the actuators to be shifted or adjusted horizontally across the reciprocating table 21, whereby either actuator 50 or 51 may engage its associated lever pin 47 or 30, so as to vibrate either lever 45 or 25, and hence to throw up either ribbon 31 or 6, to cause the same to cover the printing point during the operation of the types, while the other ribbon remains idle. At Fig. 1 the actuator 50 is shown in engagement with the lever pin 47, and the lever is elevated. The arm 29 of the other lever rests against a stop 57 fixed upon the shift rail 58, said stop serving for both levers when they are idle.

The necessary shifting of the actuators is effected by a link 59, pivoted at 60 to an ear formed upon the actuator member, and extending toward the right-hand side of the machine, being there pivoted at 61 to a bell-crank 62, and vibrating idly about said pivot 61 during the backward and forward reciprocations of the table 21. From the bell-crank extends forwardly a link 63 to a finger lever or bell-crank 64 mounted at the front of the machine over the key board. By raising the lever 64, the link 63 is thrown back, the bell crank 62 vibrates, the link 59 is thrown to the left, the actuator 50 is shifted out of engagement with the pin 47, and the actuator 51 is shifted into engagement with the pin 30, so that the lever 25 will thereafter be vibrated during the type strokes, and the ribbon 6 thrown up to cover the printing point, while the ribbon 31 remains idle. To maintain the actuators in either position, I provide a spring detent 65 upon the framework 66, to engage notches 67 formed upon the bell-crank 62.

Preferably three notches are provided, so that the detent 65 may hold the actuators not only at either extreme, but also in a midway position, in which neither pin 47 nor 30 can engage with its actuator; the actuators being sufficiently separated for this purpose. When, therefore, the actuator is in midway position, neither lever is vibrated, and hence the types strike directly upon the platen without an intervening ribbon, as is desired in stencil work.

It is usual in said "Underwood" machine to shift the platen up as at 1^a, Fig. 3, to enable the upper case characters to print. For this purpose a shifting frame is provided, of which the shift rail 28 forms a part. The platen 1 is journaled upon a platen frame, (not shown) which has a roll 68 to run upon said shift rail 28. The latter is

shifted up to 28^a, Fig. 3, at the case-shifting operation, and with it rise the bracket 27, the levers 25 and 45, and the ribbon carriers 23 and 40, together with the ribbons carried thereby; the deep vertical slots 52 and 53 in the ribbon actuators accommodating the up and down shift movements of the lever pins 47, 30. Thus the operation of causing either ribbon to cover the printing point at the type strokes is carried on the same whether the platen is shifted up or down.

Having thus described my invention, I claim:

1. In a typewriting machine, the combination of types, type operating mechanism, and means for winding a plurality of separate ink ribbons, of means to cause the type operating mechanism to vibrate either ribbon into and out of operative position at each type stroke, or to render the vibrating means inoperative.

2. In a typewriting machine having types, type-operating mechanism, and a platen, the combination of a plurality of sets of ribbon spools, ribbon vibrating devices, and means to cause the type-operating mechanism to vibrate the ribbon which is carried by either set of spools to cover and uncover the printing point at the type strokes, independently of the ribbon carried by the other spools, or to render the vibrating devices inoperative, at will.

3. In a typewriting machine, having types, type-operating mechanism and a platen, the combination of ribbon-vibrating devices including a pair of carriers, and means to cause the type-operating mechanism to reciprocate either carrier at the type strokes while the other remains idle, or to render both carriers inoperative, at will.

4. In a typewriting machine having a platen, types mounted to strike upon the visible side thereof, and a type-operating mechanism, the combination of ribbon-vibrating devices including a plurality of ribbon carriers mounted one in front of the other in front of said platen, and means to cause the type-operating mechanism to move either carrier to cover and uncover the printing point during the type strokes, or to render both carriers inoperative at will.

5. In a typewriting machine having a platen, types mounted to strike thereon, and a type-operating mechanism, the combination of a member reciprocated at the type strokes, by said type-operating mechanism, of a plurality of ribbon carriers, and means for operatively connecting either of said ribbon carriers to said reciprocating member, or for causing both carriers to remain simultaneously unconnected to said reciprocating member, at will.

6. In a typewriting machine, the combination with a platen and types mounted to strike upon the visible side thereof, of a plu-

rality of sets of ribbon spools, a member reciprocating at the type strokes, a plurality of ribbon carriers, a plurality of levers for operating said carriers, and means for effecting connection of said reciprocating member to either lever or to throw them simultaneously out of operation.

7. In a front strike writing machine, the combination with a platen and types mounted to strike upon the front side thereof, of a plurality of sets of ribbon spools, a plurality of ribbon carriers one in front of the other and in front of the platen, a pair of independently operable levers mounted side by side and connected to a member reciprocating at the type strokes, and means for either causing said reciprocating member to operate either lever or throwing the levers simultaneously out of operation, at will.

8. In a typewriting machine, the combination with a plurality of ribbon carriers, of a member reciprocating at the type strokes, a pair of actuators mounted upon said reciprocating member, one for operating each of said ribbon carriers, and means for rendering either actuator effective while the other is idle, or for rendering both actuators ineffective during the reciprocations of said reciprocating member, at will.

9. In a typewriting machine, the combination with types and a platen, of a plurality of ribbon vibrating devices each including a projecting pin, a member reciprocating at the type strokes, and a device upon said reciprocating member and provided with openings for said pins, and adjustable means for adjusting said device so that one opening may engage one pin thereby to actuate the corresponding ribbon vibrator, while the other opening is out of engagement with the other pin, and for simultaneously throwing both of said openings out of engagement with the pins, as desired.

10. In a typewriting machine, the combination with types and a platen, of a plurality of ribbon vibrating levers having projecting pins, a member reciprocating at the type strokes, a device mounted upon said reciprocating member and having openings for engaging said pins one at a time, adjustable means for adjusting said device in engagement with either of said pins and for throwing it out of engagement with both of said pins simultaneously; and means for detaining said device where so adjusted.

11. In a typewriting machine, the combination with types and a platen, of a plurality of ribbon carriers, levers connected to said carriers, a member reciprocating at the type strokes, actuators mounted upon said reciprocating member and connectible to either of said levers at will, a finger piece mounted upon the framework of the machine, means connecting said finger piece to said actuators, and means for detaining said

actuators simultaneously in an inoperative position or in a position to operate either one or the other of said levers.

12. In a typewriting machine having a platen and types mounted to strike upon a visible side thereof, the combination of two pairs of ribbon spools having their ribbons superposed between the spools, means for winding the ribbons upon both pairs of spools, ribbon-vibrating devices, and means to render the vibrating devices inoperative or to cause either ribbon to be vibrated to cover and uncover the printing point at the type strokes independently of the other ribbon.

13. In a typewriting machine having a platen and types mounted to strike upon the front thereof, the combination of a pair of ribbon spools in front of the platen, spool-

winding means, an endless ribbon surrounding said spools and their ribbon, spools whereon said endless ribbon runs, ribbon-vibrating devices, and means to render the vibrating devices inoperative or to cause either ribbon to be vibrated to cover and uncover the printing point at the type strokes independently of the other ribbon.

14. In a typewriting machine, the combination of a plurality of ribbons, vibrators for the ribbons, actuating mechanism for said vibrators, and means movable to connect any vibrator independently to said actuating mechanism and to disconnect all of said vibrators from said actuating mechanism.

EDWARD F. KUNATH.
